(57) **CLAIM**

I claim the ornamental design for a spinner display unit, as shown and described.

DESCRIPTION

FIG. 1 is a front view of a spinner display unit embodying the present invention, the back view being a mirror image thereof. FIG. 2 is a left side view of the spinner display unit shown in FIG. 1, the right side view being a minor image thereof. FIG. 3 is an enlarged top view of the spinner display unit shown in FIG. 1.

FIG. 4 is an enlarged bottom view of the spinner display unit shown in FIG. 1; and,

FIG. 5 is a perspective view of the spinner display unit shown in FIG. 1.
